UNITED STATES PATENT OFFICE.

JAMES H. SMITH AND RHEA GORDON SMITH, OF WATERTOWN, MASSACHUSETTS; SAID RHEA GORDON SMITH ASSIGNOR TO SAID JAMES H. SMITH.

OIL BURNER.

Application filed March 24, 1923. Serial No. 627,465.

This invention relates to oil burners and has for its objects to provide a novel burner comprising burner tubes having burner openings and arranged so that the mixture 5 of vaporized oil and air will be delivered to the burner tubes in such a way that it will be distributed to the burner openings of the tubes uniformly whereby the flames produced at all the openings will 10 be substantially of the same intensity; to provide a novel form of burner tube which is divided longitudinally to form a delivery chamber which communicates with the burner openings and a distributing chamber 15 into which the mixture of vaporized oil and air is fed, said partition having ports therein centrally thereof whereby the gaseous fuel in the distributing chamber will be delivered to the delivery chamber centrally 20 thereof; to provide a novel vaporizing element for vaporizing the oil which is burned; to provide a novel hood arrangement for the vaporizing tube which functions both as a means for starting the burner and also functions 25 to concentrate the heat on the vaporizing tube so as to secure a more complete vaporization; to provide an oil burner specially designed for use in a kitchen range and which is constructed so that it will deliver 30 the heat laterally against the water front and the oven as well as upwardly against the top, and otherwise to improve oil burners in various respects all as will be more fully hereinafter set forth.

In order to give an understanding of our invention we have illustrated in the drawings a selected embodiment thereof which will now be described after which the novel features will be pointed out in the appended 40 claims.

Fig. 1 is a sectional view showing our improved burner as it might be applied for the heating of a cooking range;

Fig. 2 is a section on the line 2—2, Fig. 1;

Fig. 3 is an enlarged sectional view 45 through the vaporizing tube;

Fig. 4 is an enlarged sectional view on substantially the line 4—4, Fig. 1;

Fig. 5 is a section on the line 5—5, Fig. 4 50 with parts in elevation;

Fig. 6 is an enlarged sectional view partly broken out on the line 6—6, Fig. 2;

Fig. 7 is a fragmentary perspective view 55 showing the baffle plate or partition employed for dividing the burner tube into the

distributing chamber and the delivery chamber;

Fig. 8 is a fragmentary sectional view showing a different construction of vaporizing tube;

Fig. 9 is a section on the line 9—9, Fig. 8;

Fig. 10 is a section on the line 10—10, Fig. 1;

Fig. 11 is a section on the line 11—11, Fig. 4.

While our invention may be embodied in oil burners adapted for various purposes we have herein chosen to illustrate it as it might be embodied in an oil burner designed to be used in the fire-box of a cooking range. We desire to state, however, that our invention may be embodied in oil burners adapted for use in other locations, it simply being necessary to design the shape of the burner so that it will fit the desired location.

In the drawings we have shown at 90 a cooking range having the usual fire-box 91 and grate 92, said view showing the range in vertical section. The oil burner herein shown is adapted to occupy the fire-box 91 and to be supported on the grate 92. Said oil burner is of that type comprising a plurality of burner tubes having burner openings and supported at their ends by two heads, one or both of which is in the nature of a manifold and is provided with a chamber communicating with the burner tubes, a vaporizing element for vaporizing oil and means for mixing the vaporized oil with air and delivering it to the chamber of the manifold.

In our present invention we have provided a burner involving two rows of burner tubes, one arranged above the other. These burner tubes are indicated generally at 1 and 2, the burner tubes 1 being those in the upper row and the burner tubes 2 being those in the lower row. These burner tubes are provided with burner openings 3 and each burner opening is preferably spanned by a perforated member 4 having relatively fine openings or perforations therein. These burner tubes are supported at their ends by two heads 5 and 6, said heads being provided with annular recesses 7 into which the ends of the tubes fit. The tubes and heads are shown held in assembled relation by means of tie rods 8 which extend through the tubes and through the heads. This makes a construction which is easy to assemble since the

assembling operation involves merely placing the ends of the tubes in the recesses 7 of the heads and inserting the tie rods 8 and tightening the nuts 9 thereon.

5 The head 5 is made in the form of a manifold, it having a chamber 10 therein which communicates with all of the burner tubes through openings 11. The burner also involves a vaporizing element for vaporizing 10 the oil and means for mixing the vaporized oil with air, said mixture being delivered to the manifold 10 from which it is distributed to the various burner tubes.

The vaporizing of the oil is accomplished 15 in a vaporizing tube 12 which is herein shown as situated between the two rows of tubes and directly over the center tube 2 of the lower row. This vaporizing tube 12 extends through an opening 13 in the head 6 and is connected to a supply pipe 14 by which the oil is supplied thereto. The delivery end of the vaporizing tube 12 has a delivery head 15 secured thereto which is provided with a chamber or passage 16 with 20 which the interior of the tube 12 communicates, said head having a relatively small delivery port 17 at its upper portion which communicates with the upper end of the chamber 16 and through which the vaporized 25 oil is delivered. When the burner is in operation the vaporizing of the oil in the tube 12 results from the heat generated by the burner openings in the central burner tube 2 which is situated directly under the vapor- 30 izing tube.

In the operation of a burner of this type it is important to keep the delivery orifice 17 unobstructed for if it becomes clogged with carbon the burner does not function 40 properly.

We have herein provided filtering means within the vaporizing tube 12 which serves to filter the oil and the oil vapor as it is formed and to remove therefrom any free 45 carbon or other solid matter which would be likely to clog the delivery opening 17, and in addition we have provided a screen device which is located in the chamber 16 and which helps to eliminate any solid matter 50 from the vaporized gas. Filtering material of various kinds may be used in the vaporizing tube 12. In Fig. 2 we have shown filtering material in the form of gravel 18, said gravel being retained in the tube at each 55 end by means of a screen member 19 which is inserted into the tube. In Figs. 8 and 9 we have shown a different form of filter which comprises a plurality of disks 20 of fire-clay or other material, which disks are 60 each provided with a plurality of small ports or passages 21 extending therethrough. The faces 22 of the disks are preferably concaved so that chambers 23 will be formed between adjacent disks. This construction is 65 highly advantageous because as the oil vapor

passes through the successive disks and into the various chambers 23 it is rendered homogeneous and any carbon particles or other solid matter will become deposited on the disks so that the gaseous mixture which is 70 delivered from the opening 17 will be free from material which would be apt to clog said opening.

Located in the chamber 16 is a screen member which may be in the form of fine 75 wire mesh. The screen member may have any appropriate shape so long as it forms a screen which is in the path of all gases as they pass through the chamber. This screen forms an added means for eliminating 80 any solid matter in the vaporized oil. In Fig. 3 the screen is shown at 24 and it is in the form of a wire gauze basket and if desired we may place some fibrous material 25 in the basket. In this case the screen 85 member 24 will function both as a filter and as a screen. The head 15 is shown as provided with an opening 26 directly beneath the member 24, which opening is closed by a threaded plug 27. The purpose of this 90 construction is to provide means whereby the screen 24 can be readily removed and replaced.

As the vaporized oil is delivered from the delivery orifice 17 it is mixed with air and 95 the air mixture delivered to the chamber 10 and the manifold 5. This mixing of the vaporized oil and air is accomplished in a mixing chamber 28 herein formed by a tubular member 31 carried by the manifold 100 5 and communicating therewith at one end through an opening 29, the other end 30 of the member being open. This open end 30 is situated adjacent the head 15 and the arrangement is such that the jet of vaporized 105 fuel delivered from the orifice 17 will be directed into the mixing chamber 28. In actual practice this jet of vaporized oil is delivered from the orifice 17 with considerable force so that a slight suction will be 110 created which will draw air into the chamber 28 where it becomes mingled with the vaporized oil. This mixture of air and vaporized oil is delivered to the chamber 10 of the manifold and from thence to the 115 burner tubes.

We have found from practice that with the arrangement of burner tube shown in Fig. 2 a mixture of oil vapor and air which is delivered to the manifold 10 tends to flow 120 more freely to the burner tubes at the corners than to the center burner tubes and in order to provide for uniform delivery of this gaseous mixture to all the tubes we propose to make the outer wall of the chamber 10 125 with baffle plates or ribs 55 which extend vertically and form between them a shallow vertically-extending channel 56. The mixture of oil vapor and air is delivered to the chamber 10 centrally thereof and the baffle 130

plates 55 are of sufficient extent so that they tend to direct a proper portion of the gaseous mixture vertically to the center tubes. In this way an even distribution of the mixture to all the tubes is provided so that all the burner tubes will be operating alike.

5 We have herein illustrated a hood 32 which encloses the mixing chamber and the 10 head 15.

The head 6 is also shown as having a chamber 33 therein which communicates with the burner tubes, said head thus also 15 functioning as a manifold which tends to 15 equalize the distribution of gaseous fuel to the various burner tubes.

Another feature of our invention relates 20 to a construction by which an even uniform flame may be secured throughout the entire length of each burner tube. This is accomplished by dividing the burner tubes longitudinally into two chambers, one of which 25 communicates with the burner openings and the other of which communicates with the manifolds, said chamber communicating 30 with each other at the central portion of the tube. With this arrangement the gaseous mixture will be delivered to one chamber of each tube from the manifold and will be delivered 35 from said chamber to the other chamber centrally of the tube and will thus be evenly distributed to the various burner openings.

Referring to Figs. 1, 2 and 6, for instance, 40 it will be seen that the burner tubes 1 are divided longitudinally by horizontal partitions 34 which divide the tubes into a delivery chamber 35 above the partition that communicates with the burner openings 3 and a second chamber 36 beneath the partition, which we have termed a distributing chamber. The delivery chamber 35 has no direct communication with the chambers of the manifold, as the partition 34 is provided 45 with end walls 37 which close communication between the ends of the chamber 35 and the manifolds. The lower chamber 36, however, communicates with the manifolds through the openings 11 so that the gaseous mixture from the chamber 10 of the manifold 50 is delivered to the distributing chamber 36 through said opening 11.

The two chambers 35 and 36 communicate 55 with each other at the central portion of the tube through one or more ports 38 that are formed in the partition 34. With this arrangement the gaseous mixture will be delivered from the chamber 10 of the manifold into the distributing chamber 36 and from 60 the latter will be delivered to the delivery chamber 35 at its central portion. The gaseous mixture will then be distributed in each direction in the delivery chamber and thus a substantially uniform pressure will 65 be maintained at all of the burner openings.

This ensures an even flame throughout the length of the burner tube.

A convenient way of forming the partitions is that herein illustrated in which each partition is formed in two sections, each section having at one end the semi-circular flange that constitutes the wall 37 and at the other end a similar wall 39 which is provided with an opening 40. The partitions are held in place by means of screws 41 70 which are inserted through the burner tube and screw into the walls 37 and the portions 39 as clearly shown in Fig. 6.

We have referred above to the perforated members 4 spanning the burner openings. 80 These members can be formed by taking a curved sheet of finely perforated metal and placing it inside of the burner tube beneath the burner openings and between said tube and the portions 37, 39 of the partition. 85 This sheet metal member is provided with openings 42 for the reception of the screws 41, said openings being considerably larger than the screws so as to allow for expansion and contraction. The partition members 34 90 and their end walls 37, 39, therefore, serve not only to divide the burner tubes into the distributing chambers and delivery chambers but they also serve to hold the perforated member 4 in place. 95

Another feature of our invention relates 100 to a hood device which is associated with the vaporizing tube and which functions both as a means for starting the burner and as a means for concentrating the heat of the 105 lower central burner tube on the vaporizing tube. This hood device is indicated at 43 and is in the form of a hood adapted to embrace the vaporizing tube. This hood member is herein shown as supported on two cradles 48 which extend transversely across the tubes of the lower row and are secured thereto by suitable screws 49. Each cradle is provided centrally with a curved seat 50 on which the vaporizing tube 12 rests and each 110 cradle is also provided with recesses 51 to receive the lower edges of the hood 43 as shown in Figs. 4 and 11. This hood 43 has openings 46 at its upper side and the lower edges thereof extend below the vaporizing tube and nearly to the center burner tube of 115 the lower row. When this center burner tube is operating the hood member 43 serves to concentrate the heat from the burner openings 3 therein onto the vaporizing tube 120 so that the vaporization of the oil will be more effectively accomplished. The lower edges of the hood 43 are trough shape as shown at 44 and are designed for use in 120 starting the burner. This is done by pouring alcohol, gasoline or other priming fuel into the troughs 44 and then lighting such fuel. The heat from this lighted priming fuel will heat the vaporizing tube 12 sufficiently 125 to vaporize the oil therein and thus 130

start the burner. The hood 43 is removably sustained on the cradles 48 thus facilitating the filling of the troughs with the priming fluid.

If desired, a suitable wicking 45 may be placed in the troughs which will absorb the priming liquid and thus retain it while the hood is being replaced in the burner. The hood is shown as having a finger piece 47 extending therefrom by which it may be manipulated. In using the hood 43 as a lighter it may be removed from the burner as above described and the priming fuel poured into the troughs 44 after which the lighter will be replaced and the priming fuel lighted by means of a taper or in some other suitable way. The burning of the priming fluid will start the vaporization of the oil in the vaporizing tube 12 and as soon as the 20 vaporized oil and air mixture reach the burner openings 3 the burner may be lighted by means of a taper. Sometimes the flame from the lighter is sufficient to automatically light the burner tubes after the vaporizing process has been continued sufficiently long.

The end walls 52 of the recesses 51 serve as a means for positioning the hood and ensuring that it will always be properly located when it is replaced over the vaporizing tube.

The burner tubes of the top row have their burner openings in the upper side and thus throw the heat upwardly. The two outside burner tubes 2 of the lower row have the burner openings in the side thereof as shown best in Fig. 2 so that the flame from these burner tubes will be directed laterally, one burner tube operating to heat the water front and the other assisting in heating the oven. If the baffle plates 34 are used in the tubes of the lower row then the baffle plates of the outside tubes of said lower row will have the inclined arrangement shown in 45 Figs. 2 and 4 since the burner openings in these tubes are on the side thereof.

We claim.

1. In an oil burner, the combination with a burner tube having burner openings and divided longitudinally into a distributing chamber and a delivery chamber, the latter communicating with the burner openings and the two chambers having communication with each other at the central portion 50 of the tube only and means to deliver a gaseous fuel mixture to the distributing chamber at the end of the tube, whereby said mixture is delivered to the delivery chamber centrally of the tube and thence to the 55 burner openings.

2. In an oil burner, the combination with a plurality of burner tubes having burner openings and being divided longitudinally into a delivery chamber which communicates 60 with the burner openings and a distributing

chamber, said chambers communicating centrally of the tube, of a manifold head having a chamber communicating with the distributing chambers of the tubes, and means to deliver to the chamber of the manifold 70 a mixture of vaporized oil and air.

3. In an oil burner, the combination with a burner tube having burner openings, of a partition member separate from the tube and extending longitudinally thereof and 75 having semi-circular walls at its ends, means for securing said walls to said tube, whereby the partition is supported, said partition dividing the tube into a delivery chamber which communicates with the burner openings and a distributing chamber and also having ports therein centrally of the tube forming a communication 80 between said chambers, and means to deliver a mixture of vaporized oil and air to the distributing 85 chamber at the end of the tube.

4. In an oil burner, the combination with burner tubes having burner openings, of a partition member extending longitudinally of each tube and having semi-circular walls 90 at its ends, means for securing said walls to said tubes, whereby the partition is supported, said partition dividing the tube into a delivery chamber which communicates with the burner openings and a distributing chamber and also having ports therein centrally of the tube forming a communication 95 between said chambers, a manifold to which the tubes are connected and which has a common chamber communicating with the distributing chamber of all the tubes, and means to deliver vaporized oil and air to the manifold.

5. In an oil burner, the combination with burner tubes having burner openings, of a partition member extending longitudinally of each tube and having semi-circular walls 100 at its ends, means for securing said walls to said tubes whereby the partition is supported, said partition dividing the tube into a delivery chamber which communicates with the burner openings, and a distributing chamber and also having ports therein centrally of the tube forming a communication 105 between said chambers, a perforated member within each burner tube and located between the latter and said walls, and retained in place by the means for securing said walls to the tube, said means being constructed to provide for expansion and contraction of the 110 perforated member, and means to deliver vaporized oil to the ends of the tubes.

6. In an oil burner, the combination with a burner tube having burner openings therein at which combustion takes place, a vaporizing tube for vaporizing oil and delivering it to said burner tube to be burned thereat, said vaporizing tube having within it a plurality of perforated disks each having a 115 recessed face.

7. In an oil burner, the combination with two up-standing end members or heads, one of which is hollow and constitutes a manifold, of a plurality of burner tubes extending from one end member to the other and arranged in upper and lower series, all the burner tubes communicating with the chamber of the manifold member and receiving their fuel supply therefrom, a horizontally-arranged mixing chamber situated between said series of tubes and communicating at one end with the chamber of said manifold head, the other end of said mixing chamber being open, a vaporizing device separate from the burner tubes and situated between the two series of tubes, said vaporizing device comprising a vaporizing tube, a discharge head rigid with the tube and having a discharge opening directed into the open end of the mixing chamber.
8. In an oil burner, the combination with two up-standing end members or heads, one of which is in the form of a manifold, of a plurality of burner tubes supported by said heads and arranged in upper and lower series, all the burner tubes communicating with the manifold head, a horizontally-arranged mixing chamber situated between said series of tubes and communicating at one end with said manifold head, the other end of said mixing chamber being open, a vaporizing device separate from the burner tubes and situated between the two series of tubes, said vaporizing device comprising a vaporizing tube, a discharge head rigid with the tube and having a discharge opening directed into the open end of the mixing chamber, and tie rods extending through certain of said burner tubes and tying the heads together.
9. In an oil burner, the combination with a burner element, of a vaporizing tube situated above said burner element and a hood adapted to embrace the vaporizing tube, said hood having an open top and also an open bottom and its lower edges trough shape and thereby providing receptacles for priming fuel.
10. In an oil burner, the combination with a plurality of burner tubes, of cradle members supported on said tubes, a vaporizing tube, and a hood adapted to embrace the vaporizing tube and to be removably supported on the cradles, said hood having pockets to receive priming fuel.
11. In an oil burner, the combination with a plurality of burner tubes, of cradle members supported on said tubes, each cradle member having a rest, a vaporizing tube seated on said rests, and a hood adapted to embrace the vaporizing tube and to be supported on the cradles.
12. In an oil burner, the combination with a plurality of burner tubes, of a manifold at one end of said tubes having a chamber communicating with the tubes, means to deliver a mixture of vaporized oil and air into the manifold, and ribs situated within the manifold and extending in the general direction in which said mixture flows through the manifold, said ribs serving to guide the vaporized oil and secure an even distribution of it to the various burner tubes.
13. In an oil burner, the combination with two horizontal rows of burner tubes, of a manifold at one end of said tubes having a chamber communicating with the tubes, means to deliver a mixture of vaporized oil and air into the manifold, means within the manifold to secure an even distribution of the vaporized oil to the various burner tubes, said means including vertically-extending ribs on one wall of the manifold forming between them a channel to direct a suitable portion of the vaporized fuel to the central burner tubes of each row.
14. In an oil burner, the combination with burner tubes having burner openings, each tube being divided longitudinally into a distributing chamber and a delivery chamber, the latter communicating with the burner openings and the two chambers communicating only centrally of the burner tube, a manifold communicating with the distributing chambers of the burner tubes at one end thereof, a mixing chamber communicating with the manifold, a vaporizing tube, a discharge head having a chamber therein communicating with the vaporizing tube and also having a discharge orifice to deliver vaporized oil into the mixing chamber, means for filtering and screening the vaporized oil in the vaporizing tube and head of the discharge chamber, and means within the manifold to secure a proper distribution of vaporized oil to the various burner tubes.

In testimony whereof, we have signed our names to this specification.

JAMES H. SMITH.
RHEA GORDON SMITH.
